UNITED STATES PATENT OFFICE.

ISAAC BEST, OF LAWRENCE, MASSACHUSETTS.

WOOL-COMBING MACHINE.

SPECIFICATION forming part of Letters Patent No. 355,296, dated January 4, 1887.

Application filed January 19, 1885. Serial No. 153,305. (No model.) Patented in England January 31, 1885, No. 1,407.

To all whom it may concern:

Be it known that I, ISAAC BEST, of Lawrence, in the county of Essex and State of Massachusetts, have invented a new and useful 5 Improvement in Wool-Combing Machines, which will, in connection with the accompanying drawings, be hereinafter fully described, and specifically defined in the appended claims.

This invention has for its object certain improvements in wool-combing machines, whereof the well-known "Noble" comb is an example, and it is shown in the accompanying drawings, in connection with the usual parts of that comb, and will, in connection with said 15 drawings, be hereinafter fully described and claimed.

English Patent No. 2,189, dated June 23, 1873, and granted to Thomas Whitehead and Henry Walton Whitehead, for the "invention 20 of improvements in Noble's combing-machines," representing in the drawings thereof a machine of the class to which my invention relates.

In the drawings, Figure 1 is a perspective view, taken as viewed from the interior of the machine, and showing a section thereof with my improvements thereto applied. Fig. 2 is a vertical radial section taken as on line Z, Fig. 1, and showing in elevation all beyond that line 30 as viewed from the right in Fig. 1. Fig. 3 is a top or plan view of the parts shown in Fig. 1. Fig. 4 is a view similar to Fig. 3, but omitting my improvements, and adding the drawing-rolls and coacting belts. Fig. 5 is a 35 side elevation of my improved incline-bar, by which the sliver-boxes are vertically actuated. Fig. 6 is a view similar to Fig. 5, showing said bar as heretofore formed. Fig. 7 is a detached elevation showing my auxiliary comb, its carrier and returning-spring. Fig. 8 is a detached elevation showing the cam and lower part of the vibrating lever by which the auxiliary comb is horizontally reciprocated. Fig. 9 is a detached sectional elevation, the section 40 being taken on a radial line through the large circle-comb, and the elevation showing my auxiliary dabbing-brush and part of the arm by which it is supported and actuated. Fig. 10 is a radial vertical section through the circular bed of the machine, and showing a sliver-box, the sliver and guide, the box being shown

as with its vibrating end resting on said bed. Fig. 11 is a view similar to Fig. 10, but showing the sliver-box as at 2, on the bar shown in Fig. 5. Fig. 12 is a similar view, but showing the sliver-box as resting on said bar at 3. Fig. 13 is also a similar view, but showing the sliver-box as resting on said bar at 4. Fig. 14 is likewise a similar view, but showing the sliver-box as resting at 5 on said bar. Fig. 15 55 is a similar view, but showing the sliver-box as resting at 6 on said bar.

In said drawings, A represents the circular rotating bed on which the several sliver-boxes B are pivotally mounted in the usual manner, 60 as shown. The sliver is shown at *a* as passing from the ball at the base of the machine, through guides C, and thence into the boxes, and *b* represents the large circle comb plate, all said parts being arranged to revolve around 70 a common center, and to operate in the well-known manner.

The incline-bar for vertically actuating the sliver-boxes is shown at *d*, the same being secured in position by rod *e*. The usual knives, 75 which raise the sliver above the teeth in comb-plate *b*, are shown at *c*, and *f* represents the guide or cover on which the sliver moves after being raised by knives *c*, till it arrives at the tangential junction of the larger circle-80 comb plate *b* and the lesser circle-comb *i*. The usual feeding-plate is shown at *g*, supported by arm *h*.

In my improved machine I arrange the feeding-plate *g* at a greater distance than heretofore from the small circle-comb *i*, and I employ an additional set of knives, (shown at *j*, Fig. 1.) I also form the incline-bar *d* with the elevations and depressions shown in Fig. 5, instead of with the usual single elevation, 85 as shown in Fig. 6. I further employ an additional dabbing-brush, *k*, and a reciprocating drawing-comb, *l*, said brush and comb being actuated in the manner and by means next to be described. The dabbing-brush *k* is carried 90 by the lever *m*, having at its outer end the horizontal slot *m'*, the said brush being provided with a shank, *k'*, having a vertical slot, *k''*, through which and the slot *m'* passes the attaching-bolt *m''*, (see Figs. 1 and 2,) so that 95 the said bolt has a capability of being adjusted not only vertically in reference to its

proximity to said lever, but laterally with reference to its distance from the pivot *n*, on which the lever vibrates. Said lever is actuated by pitman *p*, which is vertically reciprocated by wrist-pin *q* in crank-disk *s*, mounted on and driven by arbor *t*, which also carries pinion *u*, engaged and driven by gear *v*, secured on arbor *w*, which latter also carries the bevel-gear *x*, engaged and driven by a similar gear, 10 *y*, secured on and driven by vertical arbor *z*, which may be, and preferably is, rotated by a pinion, 37, secured thereon below the bed *D* of the machine, said several parts being preferably secured to bed *D* by a small supplemental 15 bed, *E*.

The auxiliary comb *l* is mounted on a carrier, 8, Fig. 7, to which it is secured by bolts 9, which pass through slots 10 in the carrier, and are secured in the comb. A spiral spring, 20 11, is at one end attached to a small stud secured in the carrier and at the other to one of the bolts 9, so as to automatically return the comb to the position shown in said Fig. 7 when liberated from the sliver, which latter, by the 25 rotary movement of the comb *b*, will, when comb *l* is engaged therein, move said comb *l* coincidentally with said comb *b*. Said comb *l* has also an automatic rising-and-falling motion, for the purpose of engaging and releasing the sliver, 30 and it has also a horizontal reciprocating movement toward and from the comb *b*. This last movement is secured by means of the following devices: An arm, 12, extending from carrier 8, passes through and is supported by bearing 35 21. It is also pivotally connected with rocking lever 13, pivoted upon stud 14, and carrying at its lower end a pin, 15, which engages in the groove in the side of cam-disk 16, mounted on and rotated by arbor *w*, driven as described. 40 This arrangement of devices will, from the form of the cam-groove shown in Fig. 2, impart to comb *l* a movement toward and from comb *b* at each revolution of arbor *w*.

To impart the rising-and-falling motion to 45 comb *l* an eccentric, 17, is also secured on said arbor *w*, the strap 18 of which is pivotally connected with a stud, 19, rigidly secured to rod 20, which passes through and slides in bearing 26. Upon the top of said rod 20 is secured 50 the bearing 21 of arm 12 of the described comb-carrier 8, and by the rotation of eccentric 17 said rod 20, its cap or bearing 21, and the comb-carrier 8 and comb *l* will be vertically reciprocated to an extent sufficient to engage 55 and disengage teeth 27 with and from the fiber in comb *b*. The cam 16 and eccentric 17 are so arranged that the rising motion of the comb will occur when it is close to comb *b*, as shown in Fig. 2, while its falling motion takes 60 place when it is farthest from *b*, and consequently after it has drawn the fiber, which it engages in its rising movement inward to the extent of the described horizontal movement. A clearer, 22, is attached to and supported by 65 fixed arm 23, it being arranged to slide linearly thereon by means of a slot in its arm 35 and a bolt passing through the same into said

arm 23. In the arm of said clearer is a pin, 25, between which and arm 23 is arranged the spring 24, secured at its fixed end to arm 23, 70 and so arranged as to habitually force clearer 22 toward the teeth of comb *b*, as shown in Fig. 2, yet allowing the clearer to be moved inward by the engagement therewith of the teeth of the comb when it moves inward. 75

The operation of the machine, when provided with my said improvements, is described as follows: As the slivers respectively pass under feeding-plate *g* their boxes *B* will pass up over elevation 2 of incline-bar *d*, Fig. 5. 80 This raises the boxes to the position shown in Fig. 11, and the angle thus produced between the box and bed *A* by such change of position of the box from that shown in Fig. 10 serves to increase the length of sliver projecting beyond the mouth of the box. As the boxes pass toward the end of feeding-plate *g* they move down into depression 3 in bar *d*, as shown in Fig. 12, thereby slightly folding between them and said comb *b* the increased length of 90 sliver which resulted from the rise of the boxes at 2 on bar *d*. As the boxes pass on and the slivers are liberated from the plate *g* they are raised clear of the teeth of comb *b* by knives *j*, and at the same time the boxes are correspondingly raised by elevation 4 of bar *d*, as 95 shown in Fig. 13, whereby the slivers will by their inherent elastic expansion extend themselves as far inside of comb *b* as they were extended from the boxes by the rise of the same 100 at elevation 2 of said bar, as shown in Fig. 11. As the boxes next pass down into depression 5 of bar *d*, as shown in Fig. 14, the dabbing-brush *k* depresses the fiber into the teeth of comb *b*, when comb *l*, by its described rising action, will 105 engage the fiber thus extending inside comb *b*, and by the backward movement of said comb *l* the short fiber or "noil," as it is termed, will be drawn close to the end of the fiber, thereby leaving that portion of the fiber between combs *b* and *l* cleared and freed from 110 the short fiber or noil. Said comb *l* (by its sliding action on its carrier 8, as already described, and as shown in Fig. 7) travels with the fiber as the same is carried along by rotary 115 comb *b*, and is depressed and cleared therefrom at the moment when it is at the end of its inward movement, and is then returned by the action of its spring 11, as before stated. The length of said comb *l* is such that it thus 120 acts several times upon the same fiber, and it is provided, as shown in Fig. 7, with sections of finer and coarser teeth, in order that when first acting on the slivers and arranging the longer fibers the coarser teeth shall be operative, and when the noil is largely drawn to the end of the slivers and the long fibers arranged, then the finer teeth shall complete the work. After the fiber has been fully acted on by comb *l* the boxes mount elevation 6 of 130 bar *d*, as shown in Fig. 15, and coincidently therewith the slivers or fiber is raised from the teeth of comb *b* by clearing-knives *c*, whence the fiber passes onto and along guide

f, which terminates at the point of nearest approach of combs *b* and *i*, where, as soon as the fiber leaves said guide it is sunk into said rotary combs by the usual dabbing-brush, 28, 5 thereby driving the noil, already gathered near the ends of the fiber, closely among the teeth of small comb *i*. As the slivers are raised clear of comb *b* by the action of knives *c*, and the rising of the sliver-boxes upon elevation 10 6 of bar *d*, the fiber, which by the action of comb *l* is somewhat stretched, will retract toward said boxes to an extent to bring the center of that portion which has been cleared by said comb *l* at the dividing-line between 15 combs *b* *i*, where they most nearly approach each other, and so that said cleared fiber will be sunk equally in each of said combs by brush 28. As the combs move on, and part of the separating fiber is taken by each, that which 20 remains with and projects inward from comb *b* is extracted by the drawing-rolls 30 in the usual manner, and is thence carried by belt 31 through belt-guide 32, and thence by belt 34 to drawing-rolls 33, where the two slivers re- 25 unite and pass on to the usual receptacle, while the noil which had been by reciprocating comb *l* gathered at the inner end of the slivers, so as to be driven into comb *i*, as described, and which there remains while rolls 33 withdraw 30 the long fibers by engaging their ends farthest from the noil, is raised by clearing-knives 29 and discharged from the comb.

By the operation of the means added by my invention the long and short fiber can be 35 more perfectly separated than has hitherto been practicable with rotary combs, as the noil is gathered by my supplemental comb close to the end, and so as to be sufficiently compacted in the small rotary comb to allow 40 the detached long fibers that project from the periphery of the comb to be extracted by the drawing-rolls 33 without dislodging the already-gathered noil, which is afterward discharged, as stated. Besides this, the described 45 action of my reciprocating comb *l* is such that the long fibers, which project inward from comb *b* after the separation at combs *b* *i*, are drawn from comb *b* by rolls 30 more free from the short fiber or noil than if my devices were 50 not employed.

From the foregoing it will be apparent that the horizontal inward and outward movements of the comb *l*, as well as the vertical movements thereof, are in right lines, so that the 55 teeth of the said comb are always precisely vertical, and there is therefore no tendency

for the said teeth to slip over the fiber, or for the latter to become wedged into the base of the comb, as would be the case if the said comb reciprocated in the arc of a circle. 60

I claim as my invention—

1. The combination, with the rotary combs *b* and *i* and the sliver-boxes *B*, of the feeding-plate *g*, knives *j*, brush *k*, comb *l*, knives *c*, brush 28, and bar *d*, having elevation 2, ar- 65 ranged to coact with plate *g*, the depression 3, arranged between the said plate and knives *j*, the elevation 4, arranged to coact with the said knives *j*, the depression 5, to coact with brush *k*, and elevation 6, arranged to coact 70 with the knives *c*, all substantially as set forth.

2. The combination, with the rotary combs *b* and *i* and the sliver-boxes *B*, of the feeding-plate *g*, arranged inside of the comb *b*, the knives *j*, brush *k*, comb *l*, knives *c*, the guide *f*, brush 28, and the bar *d*, having elevation 2, arranged to coact with the plate *g*, the depression 3, arranged between said plate and knives *j*, the elevation 4, arranged to coact with the said knives *j*, the depression 5, ar- 80 ranged to coact with the brush *k*, and elevation 6, arranged to coact with the knives *c*, all substantially as set forth.

3. The combination, with the rotary comb *b* and the sliver-boxes *B*, of the comb *l*, a carrier, as 8, to which the said comb is secured, said carrier having an arm, as 12, a bearing or guide, as 21, through which said arm passes, mechanism for operating said arm to reciprocate the comb *l* in a right line horizontally, 90 and mechanism for reciprocating the said bearing or guide vertically, substantially as set forth.

4. The combination, with the rotary comb *b* and the sliver-boxes *B*, of the comb *l*, hav- 95 ing teeth at that end thereof which first engages the fiber at a greater distance apart than the teeth at the other end of the said comb, and mechanism for imparting vertical and horizontal movements in right lines to the said comb *l*, substantially as set forth.

5. The combination, with the rotary comb *b*, the sliver-boxes, the comb *l*, and operating mechanism for the latter, of the clearer 22, its carrying-arm, and a spring for forcing said 105 clearer outward after it has been moved inward by the said comb *l*, substantially as set forth.

ISAAC BEST.
